US0D1107733S

(12) **United States Design Patent** (10) Patent No.: **US D1,107,733 S**
 Carrigan et al. (45) Date of Patent: ** Dec. 30, 2025

(54) **DISPLAY SCREEN OR PORTION THEREOF WITH GRAPHICAL USER INTERFACE**

(71) Applicant: **Apple Inc.**, Cupertino, CA (US)
 (72) Inventors: **Taylor Gerard Carrigan**, San Francisco, CA (US); **Jac Woo Chang**, Cupertino, CA (US); **Christian Xavier Dalonzo**, San Francisco, CA (US); **Jiaying Deng**, Sunnyvale, CA (US); **Alan C. Dye**, San Francisco, CA (US); **Thalia Jimena Echevarria Fiol**, Cupertino, CA (US); **Marcel Van Os**, Santa Cruz, CA (US); **Eric Lance Wilson**, San Jose, CA (US)

(73) Assignee: **Apple Inc.**, Cupertino, CA (US)

(**) Term: **15 Years**

(21) Appl. No.: **29/953,837**

(22) Filed: **Jul. 24, 2024**

Related U.S. Application Data

(63) Continuation of application No. 29/787,304, filed on Jun. 5, 2021, now Pat. No. Des. 1,040,831.

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.

1 Claim, 1 Drawing Sheet
